Primary Examiner — Eric Goodman*Assistant Examiner* — Ryan Harvey(74) *Attorney, Agent, or Firm* — Drinker Biddle & Reath LLP(57) **CLAIM**

The ornamental design for a electronics mounting plate with a universal hole pattern, as shown and described.

DESCRIPTION

FIG. 1 is a top view of an electronics rack with a universal hole pattern according to the present invention.

FIG. 2 is a bottom view of the electronics rack with a universal hole pattern of FIG. 1.

FIG. 3 is a rear view of the electronics rack with a universal hole pattern of FIG. 1.

FIG. 4 is a front view of the electronics rack with a universal hole pattern of FIG. 1.

FIG. 5 is a left side view of the electronics rack with a universal hole pattern of FIG. 1; and,

FIG. 6 is a right side view of the electronics rack with a universal hole pattern of FIG. 1.

The portions of the drawings appearing in broken lines are for environment only and do not form a part of the design.

1 Claim, 3 Drawing Sheets(56)
